(57) **CLAIM**

I claim the ornamental design for a wire-tensioning device for live-wire separating tool, as shown and described.

DESCRIPTION

FIG. 1 is a front elevational view of a wire-tensioning device for live-wire separating tool, showing my new design;

FIG. 2 is a rear view thereof;

FIG. 3 is a top view thereof;

FIG. 4 is a bottom view thereof;

FIG. 5 is a left side elevational view thereof;

FIG. 6 is a right side elevational view thereof;

FIG. 7 is a perspective view thereof;

FIG. 8 is a reference perspective view showing a usage state;

FIG. 9 is an enlarged partial view of the portion designated 9-9' in FIG. 3;

FIG. 10 is an enlarged partial view of the portion designated 10-10' in FIG. 1; and,

FIG. 11 is a cross-sectional view taken along line 11-11 in FIG. 1, without showing the internal mechanism.

The broken line showings of the ends in the cross section views form no part of the claimed design. The broken line showings of the power lines, ropes, supports, etc. in FIG. 8 are provided for purposes of environment and form no part of the claimed design.
